UNITED STATES PATENT OFFICE.

CLEOMAR PREJEAN, OF VERMILION PARISH, NEAR MILTON, LOUISIANA, ASSIGNOR OF
ONE-HALF TO COLLINS F. BROUSSARD, OF KAPLAN, LOUISIANA.

NUT-LOCK.

1,325,801.

Specification of Letters Patent.

Patented Dec. 23, 1919.

Application filed September 15, 1919. Serial No. 323,767.

To all whom it may concern:

Be it known that I, CLEOMAR PREJEAN, a citizen of the United States, residing in Vermilion parish, near Milton, in the parish of 5
5 Lafayette and State of Louisiana, have invented certain new and useful Improvements in Nut-Locks; and I do declare the following to be a full, clear, and exact description of the invention, such as will enable others 10 skilled in the art to which it appertains to make and use the same.

This invention relates to improvements in nutlocks; the primary object being to provide a more simple and practical lock than 15 heretofore used.

Another object is to provide a device of this character in which the locking mechanism is protected against the weather by a rotatable collar or guard.

20 With the above and other objects in view the invention consists of certain novel features of construction, and the combination and arrangement of parts as will be more fully described and claimed.

25 I attain these objects by the mechanism illustrated in the accompanying drawing, in which:

Figure 1 is a longitudinal sectional view through a nut-lock constructed in accordance with this invention, the various parts 30 of the device being shown in locked position.

Fig. 2 is a longitudinal section through the guard ring, showing the inner and outer nuts partly in elevation and partly in section and illustrating one of the pawls carried by the inner nut in engagement with the ratchet teeth disposed on the outer nut.

Fig. 3 is a transverse sectional view of the 40 nut-lock taken on the plane indicated on the line 3—3 of Fig. 1.

Fig. 4 is a bottom plan view of the outer nut; and,

Fig. 5 is a longitudinal sectional view 45 through a portion of the nut-lock, the guard ring having been disengaged from the plunger carried by the inner nut and rotated upon the latter so that its plunger receiving opening is disposed adjacent the pawl actuating cam and illustrating a tool inserted 50 through the opening into the socket of the cam for turning the same.

The embodiment illustrated includes a fastening bolt 1, having a right screw thread,

the outer end 2 of the bolt preferably being 55 reduced and provided with a left screw thread. This improved lock nut is composed of three members, an inner nut 3, an outer nut 4 and a collar or guard ring 5, the inner nut including the usual right 60 threaded central bore. The inner end of the inner nut is reduced in diameter to provide a shoulder 6 against which abuts the inwardly directed flange 7 of the guard ring 5, said guard having an opening 8 65 therein, through which is projected the reduced outer end of a spring pressed plunger 9, said plunger being seated in a suitable recess 10 formed in the collar nut.

The inner nut is provided in its outer face 70 with one or more recesses 11, preferably two in number, positioned diametrically opposite each other, each recess being elongated and provided substantially midway its length with an upstanding portion 12, in 75 the upper end of which is formed a seat for reception of an apertured ear on a pawl 13. The pawl is provided on its forward end with an inwardly directed shank 14 which serves as a guide for a coil spring 15 whose 80 function is to press the biting portion 16 outwardly beyond the outer face of the nut into engagement with the teeth on the outer nut. The inner face of the rear portion of the pawl contacts with a cam 17 which is 85 provided with an angular recess adapted to receive a suitable instrument for rotation of said cam. An opening is formed in the inner nut and communicates with the recess 11 and is aligned with the angular opening 90 in the cam 17 whereby the aforementioned instrument may be inserted for rotating the cam.

The guard ring 5 is of appreciably greater width than the inner nut 3 so that when the 95 two nuts are locked together it will be impossible to insert a tool between the nuts and depress the pawl or pawls.

An annular guide flange 18 is formed on the inner face of the outer nut 4, and is 100 adapted to be received in the annular recess formed by reducing the diameter of the bolt and by cutting away a portion of the threaded bore of the inner nut as shown at 19, said flange and annular recess serving to center 105 the outer nut when it is to be threaded on the bolt 1.

One or more studs 20 are provided on the

inner face of the collar nut 3 and are adapted to bite into the adjacent one of the members being bolted together, or they may be received in sockets specially formed for that purpose.

When the parts are to be assembled, the bolt is passed through the members to be secured together, the guard ring 5 is placed on the bolt, the inner nut 5 is then slipped in side of the guard ring so that the plunger 9 will spring into the opening in said guard ring to retain the parts against relative movement. The outer nut is then threaded on the bolt and tightened against the inner nut, thereby locking the two nuts together.

When the nuts are to be removed the plunger must be retracted so that the guard ring may be rotated for alining the opening in said ring with the rotatable cam. These parts being alined, a suitable instrument may be inserted and the cam rotated, thereby retracting the pawl or pawls whereupon the nuts may be readily separated.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the claimed invention.

I claim:

1. The combination with a bolt having right and left threads, of nuts on said threads, ratchet teeth on one of said nuts, the other nut having a recess, a pawl pivoted between its ends in said recess and movable into engagement with said teeth, and a rotatable cam mounted in said recess to retract said pawl, said cam having an instrument

engaging portion to permit rotation of said cam.

2. The combination with a bolt having 45 right and left threads, of nuts on said threads, pawl and ratchet connection between said nuts, a rotatable cam in one of said nuts for retracting said pawl and having an instrument engaging portion, a guard 50 rotatably mounted on one of said nuts and having an opening adapted for alinement with the instrument engaging portion to permit the insertion of an instrument for rotating the cam.

3. The combination with a bolt having right and left threads, of nuts on said threads, pawl and ratchet connection between said nuts, a rotatable cam in one of said nuts for retracting said pawl and having an instrument engaging portion, a guard 60 rotatably mounted on one of said nuts and having an opening adapted for alinement with the instrument engaging portion to permit the insertion of an instrument for 65 rotating the cam and means for normally retaining the guard against rotation.

4. The combination with a bolt having right and left threads, of nuts on said threads, pawl and ratchet connection between said nuts, means for permitting retraction of said pawl, a rotatable guard carried by one of said nuts and having an opening in one side, a spring pressed plunger carried by one of said nuts for reception in 70 said opening to retain the guard against rotation, said plunger being retractable to permit rotation of the guard for alining said opening and the means for permitting retraction of the pawl, whereby an instrument 75 may be inserted to retract said pawl.

In testimony whereof I have hereunto set my hand.

CLEOMAR PREJEAN.
